Melzar Tufts of Milo New York.
Lettors Patent.

The subscriber comes to inform his Lettors Patent and making part of the same containing a description in the words of himself Melzar Tufts himself of his improvement in the machine for planing and shaping Boards.

To all to whom these presents shall come Be it known that of Melzar Tufts of the Town of Milo in the County of Yates, and State of New York have invented a new and useful improvement in planing and shaping boards and that the following is a full and exact description of the construction & operation of the said machine as invented and improved by me to wit. A frame proportioned to the length and breadth of the boards, to be planed with four strong pieces running the whole length, to be placed on six posts, with six cross posts, a wheel to be made of wood or cast iron proportioned to the width of the stuff to be planed, to be placed on the top of the frame and running on two upright head blocks, with two pulleys on the shaft of the wheel, one for a sharp hand running around a drum to fasten the wheel, the other for a sharp hand running around a drum to fasten the wheel, the other four sharp hand running around a drum for the purpose of moving the carriage, on the face of the wheel at equal distances from each other, are placed four iron bits from one to two inches in width to be adjustable according to the size of the stuff, and placed at an acute angle with the face of the wheel on the reeler and edge of the wheel and of course before the bits are four or more blocks with a sharp edge on the side which are for the purpose of doing the coarse dressing of the stuff. In front of the wheel is a carriage running on the top of the frame on wood or iron truss, and on the carriage four or more upright staves, with iron blocks for the purpose of holding the boards. On the top of the carriage are two seats for the purpose of setting the carriage to or from the police.
